UNITED STATES PATENT OFFICE

VICTOR PROSPER GUILLEMIN, OF VIENNE, FRANCE

AUTOMATIC GASOLINE VAPOR GENERATOR

Application filed October 4, 1928, Serial No. 310,368, and in France October 19, 1927.

This invention relates to improvements in automatic gasoline vapor generators.

The object of the invention is the automatic continuous production of gas without any personal supervision for periods of months or weeks according to the reserve of petrol in store to give perfect homogeneity of the gaseous mixture and an unvarying composition whatever the rate of discharge.

10 In existing systems carburation of air is effected by means of a rotary compressor the movement of which produces a change in the conditions of carburation in proportion to the discharge.

15 The arrangement according to the present invention is simple without any moving elements and therefore incapable of derangement. Moreover there is no loss of petrol and any loss of mixture by leakage is avoided, hydraulic joints ensuring the conservation of the gas.

20 The gas obtained from petrol in large quantities lights immediately from a match and may be utilized in a gas stove or the like.

25 The invention will be described with reference to the accompanying diagrammatic drawing.

According to the invention the apparatus 30 comprises a centrifugal fan *a* driven by an electric motor *b* to which it is coupled, mounted on one of the walls of the tank.

35 A regulating bell *i* receives combustible mixture under pressure from the fan *a* after its passage into a carburettor *g* the pressure being imparted by the fan. This bell is in communication with the delivery system through a tube *j* which receives carburetted air at a pressure determined by the weight 40 of the bell.

A container *8* contains a quantity of water into which the bell *i* is inserted concentrically with an inner inverted chamber *l*. This container also supports and protects 45 the mechanism. A receptacle for liquid fuel

is placed inside the chamber *l* and comprises a cylindrical gasoline reservoir *m* provided at its center with a guide tube *n*. The wall of said tube is provided with openings *o*, *o'* which respectively establish fuel and air communication between the tube and the reservoir, so that an even pressure is maintained in the air space of the reservoir. The reservoir *m* may be filled by an outside tube *p*, which in practice is provided with a valve.

50 The carburettor *q* with a float *t* guided in the tube *n* follows the gasoline level in the reservoir. On its upper part it is formed with a cylindrical portion *r* closed at its upper end and enclosing a tube *s* affixed into the centre of the tube *n* at the bottom. This carburettor is provided with an airtight chamber *t* which ensures its floating on the gasoline and with a second chamber *u* above the chamber *t* communicating with the portion *r* through orifices *v* and with the interior of the tube *n* through a lateral perforated cylindrical side wall *x* having a porous surface of cloth for example. A hydraulic 55 check valve *y* having two compartments *c* and *d* is also provided.

60 At the upper end of the tube *n* is a deflector disc *w* which closes the upper end of said tube and has grooves in its lower side which establish communication between the interior of the bell *i* and the interior of said tube. As the carburetted air and the non-carburetted air pass from the tube, they 65 strike the lower side of the disc and are deflected outwardly thereby and pass through the grooves of the disc and are thereby thoroughly mixed while leaving the tube.

70 Hence a uniform mixture is at all times supplied to the bell.

75 A lever *z* automatically controls the stopping and starting of the motor *b* which is driven from a suitable source of electric power (not shown).

The operation of the apparatus is as follows:—

If the regulating bell *i* is at its lowest position the lever *z* which rests upon it is lowered and closes the switch *k* and the fan pumps air into the two compartments *c* and *d* of the hydraulic valve *y* through pipes *c¹* and *d¹*. The air compartment *c* is in direct communication with the cylindrical portion *r* of the float through a tube *e* and tube *s* and with the chamber *u* of the carburettor through the orifices *v* from which it can pass through the porous wall *x* which dips into the gasoline and becomes impregnated therewith.

The air passing to the compartment *d* can be regulated or completely stopped by a valve *g* in the tube *d¹* and from the chamber *d* passes along a tube *f* into the tube *n* where it mixes with air agitated by means of the disc *w* which gives an energetic stirring.

When the bell *i* has reached its upper position the lever *z* is raised by it and opens the automatic switch *k* and stops the motor *b*. The same movement recommences when the bell has reached its lowest position.

For slow delivery the motor operates intermittently at long intervals whilst for heavy discharges the running is almost continuous.

As the float *t* supporting the carburettor gives identical conditions at the porous surface wherever the level of the petrol may be and the amount of air carburetted is constant for any given period of time when the fan is running the consistency of the mixture is also constant.

The valve *g* allows for varying the richness of the gas obtained according to the use to which it is to be put.

For continuous running a refilling of the reservoir is all that is necessary.

The invention is not limited to the apparatus shown but includes all variations based on the same principle and may have the fan replaced by any other compressor worked manually or mechanically.

What I claim as my invention and desire to protect by Letters Patent is:—

1. Gas forming apparatus, comprising a closed casing containing a liquid hydrocarbon, a gas discharge conduit extending from the upper part of said casing, a floating carburetor in said casing, comprising a tubular member having a base float, a central tubular portion extending upwardly from said float to a point above the liquid level, and closed at its upper end, a skirt of porous liquid absorbent material placed about said float and partially immersed in the liquid in the casing, means for introducing a gas under pressure into said central tubular portion, and passage means leading from said tubular portion to the liquid immersed and non-immersed portions of said skirt.

2. Apparatus for automatically producing a gas of unvarying composition, comprising a receptacle for liquid fuel provided with a reservoir having fuel, a carburetor arranged to float in the fuel and having a porous wall and an air dome, means to supply air to the air dome, means to regulate the supply of air, a water tank in which the receptacle is arranged, a bell which encloses the receptacle and into which the latter discharges the gaseous mixture and which bell serves to cool said mixture and a service pipe leading from the interior of said bell.

3. Apparatus as claimed in claim 2, including means to cause commingling of gaseous mixtures of varying richness prior to their discharge into the bell.

In testimony whereof I affix my signature.

VICTOR PROSPER GUILLEMIN.
